UNITED STATES PATENT OFFICE.

JONAS H. FOX, OF SEATTLE, WASHINGTON.

BOILER.

Application filed September 7, 1927. Serial No. 217,952.

This invention relates to improvements in boilers and more particularly to a fire tube boiler of the externally fired type, wherein the fire box is surrounded by water legs 5 which, at their upper ends, communicate with the boiler proper and which form the walls of a fire box.

It is the principal object of the present invention to provide a horizontal, fire tube boiler of the above character embodying certain novel features in water leg construction whereby an accelerated and more satisfactory circulation of water is produced than in the ordinary construction, so that quicker 15 heating and greater boiler efficiency is obtained.

Other objects of the invention reside in the various details of construction and in the relation of parts whereby the above results 20 are accomplished and whereby a commercially practicable and very desirable boiler is produced.

In accomplishing these objects, I have provided the improved details of construction, 25 the preferred forms of which are illustrated in the accompanying drawings, wherein—

Figure 1 is a view, shown one-half in transverse vertical section and one-half in front elevation, of a boiler constructed in 30 accordance with the present invention.

Figure 2 is a longitudinal, vertical section of the same.

Referring more in detail to the drawings—

The boiler, as illustrated, comprises a 35 horizontally disposed, cylindrical shell, or boiler portion proper, designated by reference numeral 1, which is closed at its opposite ends by flue sheets 2 and 3. Communicating with the boiler at its opposite sides, 40 also at the front and rear ends, are water legs, presently described in detail, which form the walls of the fire box or combustion chamber 4; this being provided at the front end with the usual opening 5 for firing.

45 The cylindrical body portion 1 contains the spaced apart upper and lower sets of fire tubes extending from end to end thereof through the flue sheets 2 and 3. The lower set of tubes, designated by numeral 6, 50 lead forwardly from an auxiliary combustion chamber 7, provided in open communication with the rear end of the main fire box between the rear water leg and lower rear end portion of the boiler, and open into a

smoke box 8 at the front end of the boiler, 55 while the upper set of tubes 9 lead rearwardly from the smoke box 8 and into a rear smoke box, or flue connection, 10.

The water legs at the sides and ends of the fire box, or furnace, are formed by spaced 60 apart, inner and outer plates 11—12 joined in spaced relation by stay bolts 13, and are welded, or otherwise suitably fixed, to the boiler shell. The water legs at the opposite sides of the boiler, which are designated at 65 15, communicate with the interior of the boiler 1 through a plurality of spaced apart, vertical slots 16 provided in the opposite sides of the boiler shell. The water leg at the front, designated at 17, opens directly 70 across its entire end, as at 18, into the front end of the boiler, while the water leg 19, at the rear, is set back somewhat beyond the boiler end providing the combustion chamber 7, and at its upper end is curved over 75 gradually so as to terminate in a horizontally directed portion 20 which is joined with the rear flue sheet 3 and which opens into the boiler through a horizontal slot 21 that extends substantially the width of the boiler 80 at just below its diametrical center and in alignment with a horizontally extending space that is left between the upper and lower sets of fire tubes.

The most important feature of this invention 85 resides in the construction of the rear water leg and its relation to the boiler. It is readily apparent that, since the direction of circulation of water will correspond to the direction of the travel of flame or 90 heat, there will be a greatly accelerated circulation of water upwardly through the rear water leg, because of the travel of heat upwardly along this leg and into the fire tubes. Water circulating upwardly through 95 this leg will discharge into the boiler through the slot 21 with an accelerated flow which will carry it to or well toward the forward end of the boiler. In its forward flow it will be distributed laterally to the 100 slots 16 for passage to the side water legs for re-circulation back to the rear and again up through the rear leg and into the boiler.

While it is well known that boilers of a 105 type having connecting water legs at sides and ends and forming the fire box have been used for many years, it is thought to be new in the art to construct the rear water

leg, with the laterally curved upper end portion, as shown in Figure 2, and to so connect it with the boiler that the inflow of water from this leg into the boiler, accelerated by 5 the application of heat thereto and further influenced by its particular design, will be directed horizontally toward the forward end of the boiler. Heretofore, in boilers of this type, the rear water leg has connected 10 with the base of the boiler in practically the same manner as the front leg of the present type is shown, resulting in a vertical upflow of water from the leg into the boiler with an eddying effect and a retarded circulation.

The present boiler, because of the horizontal discharge of water from the leg 19, and the unrestricted space between the upper and lower sets of tubes into which this 20 water is delivered, effects a rapid and effective circulation that results in quick and effective heating with a minimum fuel consumption.

Having thus described my invention, what

I claim as new therein and desire to secure 25 by Letters Patent, is:

A horizontal fire tube boiler of the character described having an upper and a lower set of tubes slightly spaced apart to leave an intermediate, unrestricted area; said shell 30 being provided across one end with a horizontal opening aligned with said unrestricted area, water legs connected at their upper ends with the shell at its opposite ends and sides and forming the walls of a fire box; 35 the legs at opposite ends of the box being adapted, respectively, to contain downwardly and upwardly circulating water with the leg which carries the upwardly circulating water curved gradually at its upper end 40 from vertical to a horizontal direction and connected to the shell through said horizontal end opening so that the flow of water therefrom will be unretarded and delivered horizontally into the shell.

Signed at Seattle, Washington, this 22nd day of August, 1927.

JONAS H. FOX.
